UNITED STATES PATENT OFFICE.

MAX WIELAND, OF BERLIN-TEMPELHOF, GERMANY.

METHOD FOR THE MANUFACTURE OF BICHROMATE-GLUE PRINTING PLATES FOR HAND PRINTING OR PRESS DEEP PRINTING.

No Drawing. Application filed November 7, 1924, Serial No 748,487, and in Germany November 13, 1923.
Renewed September 22, 1928.

My invention relates to a method for the manufacture of bichromate-glue printing plates, especially such for handprinting and press deep-printing, and the subject-matter 5 of the invention resides in mixing a glue or an equivalent substance which is able to swell in liquid state, with a hydraulic agglutinant or cementing medium which is able to set, such as cement, gypsum, or the like, the purpose being to increase the resistant capacity 10 of the printing plates, the mixture being then applied in liquid state on to the plates or upon bands.

The admixture of the hydraulic agglutinant or cementing medium or the like, such for instance as stated, to the liquid glue of a kind as stated answers the purpose if the respective agglutinant or cementing medium is admixed to the respective glue in a proportion in which the swelling capacity of the layer of glue is not affected down to a certain depth of that layer.

As the layer of the agglutinant or cementing medium is completely penetrated by the glue it remains united firmly and organically with the layer of glue that separates at the surface of the mixture.

Owing to the admixture of the agglutinant or cementing medium the inner strength or 30 resistant capacity of the form is increased and the period of time during which the form can be utilized practically is extended in comparison to the known forms which consist only of layers of glue. To increase the 35 setting capacity of the cementing medium a certain amount of finely ground quartz can be added to the mixture.

In order to render the novel method as 40 actually used more comprehensive, there will be described in the following the accurate method of producing bichromate glue printing plates taking into consideration the known methods.

The generally known method for producing so-called photo-printing forms is based 45 on the formation of a grain of irregular shape. This production of the irregular grain layer in the upper part of gelatine which has been sensitized against light by 50 chromic acid salts is a dry process and is carried out at about 50° C. This irregular grain loses upon exposure and depending upon the action of the light more or less the quality of absorbing fatty pigments or

repelling them, and in that way it produces 55 a plate for printing.

In the present method, however, we want to produce a relief suitable for printing and which may be used directly as a recessed printing form (intaglio).

A viscous mass, that is colloid, as for instance gelatine, glues which may swell up, etc, is mixed with a hydraulic binder in order to impart to the gelatine or some other suitable acting substance the required rigidity.

For instance a substance of 10% gelatine is mixed with 2 to 4% of extremely fine ground Portland cement. But it is necessary to be very carefully on the look-out to note that the hydraulic binder must be ground 70 so fine that this addition is combined or solidified in colloidal state. It is, therefore, most advisably ground in the well known colloid grinder of Paulson, together with alcohol.

This mass which is not sensitized is then poured upon the carrier of the emulsion. The carrier may be any suitably selected material, as for instance a strip of aluminium or plates made from some other substance. 80 The mass after having been poured on it becomes rigid and the binder organically tied up with the colloid will settle downward, forming thereby a skeleton structure of carrying ribs which taper to a point upward 85 so as to have triangular cross-section. The glue itself is then near the top in excess. The specifically heavier binder, however, adheres very firmly on the lower surface to the carrier and in this way absolutely guarantees a permanent connection of the congealed 90 substance with the carrier.

These plates or strips may be prepared in the manner described in daylight, since they have not been sensitized yet. In this manner there is assured the possibility of maintaining in stock these plates or strips in larger quantities without risking the danger that they spoil in time.

If then this plate or strip is to be used, 100 it is sensitized in the darker room by immersing it for short time in a chromic acid salt solution. Then it is dried, placed underneath the negative to be printed and is exposed for a short time in a known way.

After washing out then the sensitizing salts there is obtained a tanned relief suitable for intaglio printing and which upon 105

application of the printing ink absorbs more or less of the ink.

When the printing forms have become solid they are rendered sensitive in known manner with the aid of a bichromate, and when the plates have been exposed under a photographic negative or the like they are further treated also in known manner.

I am aware of the proposal to add powdered stone to a gelatine-mass in order to serve as a filling material therefor and to render the mass more absorbing for moisture, but the powdered stone or equivalent substance employed has not been such that is capable of setting so that the particles thereof are not able to form a solid structure and to increase the resisting capacity of the printing plate, especially as regards tensile stress.

I claim:

1. In the method of producing chromic acid salt colloid printing plates the step of mixing a colloid with a hydraulic binding

substance in such proportions as to preserve the ability of the colloid to swell.

2. In the method of producing chromic acid salt colloid printing plates the steps of mixing a colloid with a hydraulic hardening and binding substance in such proportions as to preserve the ability of the colloid to swell and pouring the resulting mass on a base to harden thereon to produce a rigid layer with a chromic acid salt.

3. The method of producing chromic acid salt colloid printing plates consisting in mixing a colloid with a hydraulic hardening and binding substance in such proportions as to preserve the ability of the colloid to swell; pouring the resulting mass upon a base to harden thereon to produce a rigid layer, desensitizing said layer and exposing and developing the same.

In testimony whereof I affix my signature.

MAX WIELAND.
